CLAIM

The ornamental design for a putter head, as shown and described.

DESCRIPTION

FIG. 1 is a front elevation view of a putter head;
FIG. 2 is a rear elevation view thereof;
FIG. 3 is a top plan view thereof;
FIG. 4 is a bottom plan view thereof;
FIG. 5 is a heel-side elevation view thereof;
FIG. 6 is a toe-side elevation view thereof;
FIG. 7 is a top perspective view thereof; and,
FIG. 8 is a top perspective view showing the putter head in use.
The broken lines shown depict portions of the putter head and environment and form no part of the claimed design.

1 Claim, 6 Drawing Sheets
